United States Patent Office.

ALBERT ARONSON, OF NEW YORK, N. Y.

Design No. 4,446, dated November 1, 1870.

DESIGN FOR A COLLAR-BOX.

The Schedule referred to in these Letters Patent and making part of the same.

To all whom it may concern:

Be it known that I, ALBERT ARONSON, of the city, county, and State of New York, have invented a new and improved Design for a Collar-Box; and I do hereby declare that the following is a full, clear, and exact description thereof, which will enable others skilled in the art to make and use the same, reference being had to the accompanying drawing forming part of this specification, in which the figure is a side view of a collar-box, illustrating my improved design.

My invention has for its object to furnish an improved design for a collar-box, which shall be neat and simple and at the same time peculiar, so as to attract attention and please the taste; and

It consists in the design for a collar-box, hereinafter more fully described.

The body of the box is cylindrical in form, and is covered with paper, representing the said body as made of logs, and provided with a door and windows, and having a sign over the door bearing the name of the collar to be placed in the box.

The cover is made in the form of a low cone, and is covered with paper, representing the cover as formed of logs meeting in the apex of the cone.

I claim—

The design for a collar-box, substantially as herein shown and set forth.

The above specification of my invention signed by me this 7th day of October, 1870.

ALBERT ARONSON.
